UNITED STATES PATENT OFFICE.

BURNHAM C. STICKNEY, OF ELIZABETH, NEW JERSEY, ASSIGNOR TO UNDERWOOD
TYPEWRITER COMPANY, OF NEW YORK, N. Y., A CORPORATION OF DELAWARE.

TYPEWRITING-MACHINE.

1,349,016.

Specification of Letters Patent. Patented Aug. 10, 1920.

Application filed September 9, 1918. Serial No. 253,241.

To all whom it may concern:

Be it known that I, BURNHAM C. STICKNEY, a citizen of the United States, residing in Elizabeth, in the county of Union and State of New Jersey, have invented certain new and useful Improvements in Typewriting-Machines, of which the following is a specification.

This invention relates to the class of writing machines disclosed in the patent to Werner & Smith No. 1,132,055, in which superposed plies of web are led into the machine to be typed, and in which the platen can be displaced to permit the web to be straightened out, thereby freeing the carbon sheets which are interposed between the plies of web, so that the carbon sheets may be drawn back preparatory to typing fresh portions of the plies of web. In my application No. 240,130 is disclosed a device for automatically feeding a record sheet to produce a blank space between groups of entries upon a "condensed record" sheet, which underlies the plies of web and receives carbon impressions of all the items that are entered upon successive forms of the web. The web is usually printed with a succession of forms upon which the items are typed. The typing may not occupy many lines on the form, which is usually torn off as soon as it is typed. Upon the record sheet all of the typing for the successive forms is written compactly without extra spacing between entries, except for the spacing produced by the mechanism disclosed in said application, in which the condensed record sheet passes between special feed rolls, which during the typing operation are idle, but which operate automatically to advance the record sheet at the platen-displacing operation. The present application relates to improved and simplified means for effecting an automatic advance of the condensed record sheet.

In accordance with the present improvements, the special rolls for feeding the condensed record sheet are placed near the printing line, in order to avoid leaving an excessive blank area between the top edge and the first typed line. Preferably the rolls are placed a little below the printing line, thus leaving the extent of blank space at the top of the sheet optional. The record sheet may be of a trifle greater width than

the work webs, and the special feeding rolls may engage the side margins of the record sheet, the web passing freely through the space left between the special rolls. Preferably at each end of the platen, which may be just long enough to accommodate the work web, there is placed loosely upon the platen axle a feed roll which is of about the same diameter as the platen. For each of these rolls there is provided a pawl-and-ratchet mechanism which will operate automatically at the platen-displacing operation, to rotate the rolls simultaneously; and a spring detent is provided for each ratchet, to secure uniformity in the extent of the simultaneous movements of the rolls. Each of these rolls has a companion roll, which is normally cast off, so as not to be in use at the typing operation; but at some point in the platen-displacing operation these companion rolls are automatically restored to coöperation with the ratchet-driven rolls. The ratchets are illustrated as being operated by links which come into play by reason of the upward swinging or displacement of the platen, and preferably the record sheet is fed thereby at the upward movement of the platen. The record sheet remains under control until the conclusion of the downward movement of the platen, which restores it to typing position; at which time both the record sheet and the plies of web come under control of the usual rolls which run upon the bottom of the platen, so that all the sheets may be line-fed together during the typing operation.

Other features and advantages will hereinafter appear.

In the accompanying drawings, Figure 1 is a perspective view of an Underwood front-strike writing machine embodying the present improvements.

Fig. 2 is a sectional elevation taken from front to rear and showing the parts in their normal positions, the platen being in its depressed or typing position.

Fig. 3 illustrates the release of the hooks which normally hold the platen depressed, and also the concomitant restoration of the front or companion rolls which take part in feeding the record sheet.

Fig. 4 illustrates the platen at a point in its upward movement to permit the

straightening out of the webs. At this point the independent forward feeding of the record sheet begins.

Fig. 5 shows the displacement of the 5 platen and the forward feeding of the record sheet both completed.

Fig. 6 is a front view of the left-hand end of the platen and adjacent parts in writing position.

- 10 The plies of web 10 are led into the machine and pass forwardly along a supplemental carriage 11, to the main carriage 12. Between the plies are sheets of carbon 13, attached at their rear ends to a carrier 14, 15 which advances step by step with the work during the usual line-feeding operations, but which may be pushed backwardly from time to time in order to bring the carbons into use with fresh portions of the web. The 20 plies of web with interposed carbons pass downwardly over a bar 15 and run forwardly under and up around a revoluble platen 16, which is supported by said carriage 12. Feed rolls 17 and 18 run upon 25 the bottom of the platen.

When it is desired to straighten out the sheets, the platen is swung upward from the position at Fig. 2 to the position at Fig. 5, being for this purpose mounted upon a 30 swing-frame 19, which is hinged at 20 to the carriage. The web being now straightened out, the carbon-carrier may be caused to shift the carbons backwardly in the well-known manner.

35 The length of the platen is about equal to the width of the work web, but the record sheet 21 is made wider, to be engageable by each of two driving rolls 22 mounted loosely on hubs 16^a in juxtaposition to the ends of 40 the platen 16. During the ordinary line-feeding of the web and record sheet, these rolls 22 remain idle; but at the platen-displacing operation they coöperate with companion rolls 24 to feed the record sheet 21 45 either alone or with its overlying carbon 25; and in the latter case the carbon 25 need not be attached to the carbon-carrier 14.

A spring 26 for each companion roll 24 tends normally to press it against the driving roll 22; but for the purpose of restraining this tendency and normally keeping the two rolls out of use, each roll is mounted upon an arm 27, pivoted at 27^a, which is provided with a rearwardly and upwardly 55 extending finger 28 to rest against an abutment or stop 29. It is desirable to release these rolls 24 from said stops 29, and thereby restore the rolls 24 to working positions, before the platen begins to rise, so as to maintain 60 control over the record sheet 21; and for this purpose said stop 29 is formed as part of a hook-arm 30, the hook 31 of which normally catches over a pin or roller 32 upon the frame 19, to hold the platen down. This 65 hook-arm has a finger-piece 33, by which the

arm may be pressed back against a spring 33^a, to release the platen for its upward swing, and restore the companion rolls 24 to effective positions, as at Fig. 3.

Upon each of the driving rolls is provided 70 a ratchet wheel 34, with which engages a pawl 35, pivoted at 36 upon an arm 37 which swings freely about the platen axle 23. The power to drive this arm and pawl may be derived from the upward displacing 75 movement of the platen frame 19, so that the lifting of the platen 16 will automatically feed forward the record sheet 21. For this purpose each pawl 35 or pawl-arm 37 is

shackled or connected to an anchorage pin 80 38 provided upon the carriage 12. The connection is in the form of a shackle or loose link 39 pivoted at its forward end at 36 to arm 37, and along its rear portion having a

long slot 40, which engages the pin 38. During the first part of the upward displacement of the platen, the link rides backward idly upon the pin 38 until the link reaches about a horizontal position, and then rides idly 45 forwardly as the pivot 36 swings with the platen about the platen-frame hinge 20. Thus the position seen at Fig. 4 is reached.

The anchorage pin 38 now engages the rear end of the slot 40, so that the link 39 cannot yield, and hence the pawl 35 and arm 37 are 95 held against further bodily swinging about the platen-frame hinge 20. The movement of the platen frame about said hinge 20 continues, however, until the position seen at Fig. 5 is reached; and during this concluding portion of the stroke the unyielding pawl 35 forces the ratchet wheel 34 and roll 22 to turn upon the platen axle 23, thus advancing 100 the record sheet 21. The extent of the advance may be determined by the length of the slot 40, or the position of the pin 38; and it may be equal to two or three of the teeth of the ratchet 34. These teeth correspond in number to the teeth of the usual line-space ratchet wheel 42, and each ratchet wheel 34 105 is provided with a spring detent or check 43, which insures that the turning movement of roll 22 at one end of the platen shall be the same as that of the corresponding roll 22 at the other end of the platen, thus 115 conducting to even feeding of the record sheet. The arrangement also insures that the extent of the feeding movement of the record sheet shall be a multiple of the ordinary single-space line-spacing movement. More- 120 over the detent insures that the record sheet shall not become displaced during the downward swing of the platen to typing position.

As the platen swings back to typing position, the link 39 rides freely about the anchorage pin 38, and is detained thereby near the completion of the downward movement of the platen, so that the pawl-arm 37 swings about the platen axis; the pawl riding back idly over the teeth of the ratchet wheel 34, 125 130

being drawn by the spring 26 during this movement. In order to prevent the spring 26 from lifting the pawl 35 in Fig. 2 position, and from misplacing the pawl during the bringing of the platen back to writing position, there may be provided a stop 44 fast on the journal 45 in the frame 19 on which the platen axle is journaled. As illustrated in Figs. 3 and 4, after roll 24 has been brought into contact with the driving roll 22, as a result of the actuation of finger-piece 33, the parts carried by the swing frame 19 will remain fixed relatively to said swing frame 19 until the arm or pawl-carrier 37 is actuated by link 39 during the movement of the lifting frame from the position shown in Fig. 4 to that shown in Fig. 5. As illustrated in Figs. 4 and 5, the actuation of arm 37 by link 39 results in extending spring 26 and thereby increasing the pressure of roll 24 on the driving roll 22, thus tending to hold the record-sheet more firmly against the driving roll 22 during the actuation of the latter. While a single pawl and link have been described, it will be understood that the devices are duplicated at the ends of the platen. As soon as the platen is fully depressed, the hook-arm 30 is swung forward either manually or by means of the spring 33^a, and the abutment 29 thereon engages the finger 28 and disengages the roll at each end of the platen, so that the line-feeding movements of the record sheet may be effected by the platen and the usual bottom rolls 17, 18. To limit the upward and forward movement of the platen, the usual bumpers 46 are provided on the carriage on which the frame 19 is adapted to rest in Fig. 5 position.

The improvement in feeding the record sheet may be used in other types of machines, and in other connections.

Variations may be resorted to within the scope of the invention, and portions of the improvements may be used without others.

Having thus described my invention, I claim:

1. The combination with a carriage and a revolute platen therein, of a device whereby the platen may be lifted relatively to the carriage, feed-rolls mounted on said carriage for holding work-sheets to the platen while the latter is in depressed position, an axle for the platen, a separately-revolute portion journaled on the platen-axle, a special feed-roll carried by said lifting device to cooperate with said separately-revolute portion adapted to hold a work-sheet thereagainst, and means whereby said special feed-roll will be maintained in ineffective position relative to said separately-revolute portion while the platen is in depressed position on said carriage.
2. The combination with a carriage and a revolute platen therein, of a device whereby the platen may be lifted relatively to the

carriage, feed rolls for holding work-sheets to the platen, an axle for the platen, a separately revolute portion journaled on the platen axle, and a special feed roll for said separately revolute portion adapted to hold a work-sheet thereagainst independently of the other work-sheets, said last-named feed roll normally ineffective and adapted to be made effective automatically before the platen is lifted.

3. The combination with a carriage and a revolute platen therein, of a device whereby the platen may be lifted relatively to the carriage, feed rolls for holding work-sheets to the platen, an axle for the platen, a separately revolute portion journaled on the platen axle, a special feed roll for said separately revolute portion adapted to hold a work-sheet thereagainst independently of the other work-sheets, a catch normally holding said platen in writing position in the carriage, said special feed roll being normally ineffective, and means for making said last-named feed roll effective by making said catch ineffective.

4. The combination with a carriage and a revolute platen therein, of a device whereby the platen may be lifted relatively to the carriage, feed rolls for holding work-sheets to the platen, an axle for the platen, a separately revolute portion journaled on the platen axle, a special feed roll for said separately revolute portion adapted to hold a work-sheet thereagainst independently of the other work-sheets, a catch normally holding said platen in writing position with the carriage, said special feed roll being normally ineffective, means for making said special feed roll effective by making said catch ineffective, and a device for rotating said separately revolute portion by movement of the platen relatively to the carriage.

5. In a typewriting machine, the combination with a carriage including feed rolls, of a platen about which a work-sheet is adapted to be passed to be held against the platen by said feed rolls, a swing frame in which said platen is journaled to enable it to be swung to and from said feed rolls, an axle for said platen, a separately revolute portion adjacent each end of said platen and journaled on said axle, a special normally ineffective feed roll for each of said portions adapted to hold a work-sheet against said portions independently of the first-named feed rolls, a detent for each separately revolute portion adapted to hold a work-sheet aligned, and means for making said special feed rolls effective by moving the platen relatively to its carriage.

6. In a typewriting machine, the combination with a carriage including feed rolls, of a platen about which a work-sheet is adapted to be passed to be held against the platen by the feed rolls, a swing frame in which said

- platens is journaled to enable it to be swung to and from said feed rolls, an axle for said platen, a separately revoluble portion adjacent each end of said platen and journaled 5 on the axle, a special normally ineffective feed roll for each of said portions adapted to hold a work-sheet against said portions independently of the first-named feed rolls, a 10 detent for each separately revoluble portion adapted to hold a work-sheet aligned, means for making said last-named feed rolls effective by moving the platen and its carriage, and means for rotating said portions by said movement of the platen.
- 15 7. In a typewriting machine, the combination with a traveling carriage and a platen therein including an axle, of a swing frame in which said axle is journaled, a separately revoluble portion adjacent to the platen and journaled on the axle, a feed roll for holding 20 a work-sheet against said portion, and a detent mounted in said swing frame adapted to hold said portion against turning.
8. In a typewriting machine, the combination with a traveling carriage and a platen therein including an axle, of a swing frame in which said axle is journaled, a separately revoluble portion adjacent to the platen and journaled on the axle, a normally ineffective 25 feed roll for said portion, a detent mounted in said swing frame for holding said portion against revolving, and means for revolving said portion by swinging said frame.
9. In a typewriting machine, the combination with a traveling carriage and a platen therein including an axle, of a swing frame in which said platen is journaled on the axle, a separately revoluble portion adjacent to the platen and journaled on the axle, a normally ineffective feed roll for said portion, 30 a detent mounted in said swing frame for holding said portion against revolving, a ratchet wheel for said detent, a pawl, a mounting for said pawl journaled on the 35 platen axle, so that the pawl may engage said ratchet wheel, and a link extending from said mounting to the carriage frame and adapted to drive the pawl around the platen axle to rotate the portion.
- 40 10. In a typewriting machine, the combination with a traveling carriage and a platen therein including an axle, of a swing frame in which said platen is journaled on the axle, a separately revoluble portion adjacent to the platen and journaled on the axle, a normally ineffective feed roll for 45 said portion, a detent mounted in said swing frame for holding said portion against revolving, a ratchet wheel for said detent, a pawl, a mounting for said pawl journaled on the 50 platen axle, so that the pawl may engage said ratchet wheel, and a link extending from said mounting to the carriage frame and adapted to drive the pawl around the platen axle to rotate the portion to ad-

vance it, said link constituting part of a lost-motion connection between the carriage and the platen to enable the advance of the portion to be small relative to the movement of the platen.

70

11. In a typewriting machine, in combination, a revoluble platen, feed-rolls co-operating therewith to feed a plurality of work-sheets, including a record-sheet, the margins of which extend beyond the ends 75 of said platen, independently-revoluble members, forming extensions of said platen, to receive the margins of said record-sheet, auxiliary feed-rolls to co-operate with said members, means whereby the platen and the 80 corresponding feed-rolls may be separated, to release the work, and means, actuated by said separating means, for actuating said independently-revoluble members, and thereby advancing the record-sheet.

85

12. The combination with a carriage and a swing frame therein, of a platen journaled in said swing frame, feed rolls for holding work-sheets to the platen, an axle by which the platen is mounted in said swing frame, a separately revoluble portion journaled on the platen axle, means for holding a work-sheet against said separately revoluble portion, a pawl adapted to drive said separately revoluble portion upon the 95 swinging of said frame, and means for limiting the throw of said pawl.

90

13. The combination with a carriage and a swing frame therein, of a platen journaled in said swing frame, feed rolls for holding 100 work-sheets to the platen, an axle by which the platen is mounted in said swing frame, a separately revoluble portion journaled on the platen axle, means for holding a work-sheet against said separately revoluble portion, a pawl adapted to drive said separately 105 revoluble portion upon the swinging of said frame, a spring normally holding said pawl, a stop for the pawl upon the swing frame, and a lost-motion connection between the 110 pawl and the carriage to cause the pawl to drive the portion by movement of the swing frame.

105

14. In a typewriting machine, the combination with a traveling carriage and a platen therein including an axle, of a swing frame in which said axle is journaled, a separately revoluble portion adjacent the platen and journaled on the axle, a feed roll for holding a work-sheet against said 115 portion, a driving pawl for said portion, a member journaled on the platen axle carrying said pawl, and a lost-motion connection between the carriage and the pawl for causing it to drive the portion by the swinging 120 of the frame.

125

15. In a typewriting machine, the combination with a traveling carriage and a platen therein, of a swing frame, an axle for said platen journaled in said frame, line- 130

space mechanism for turning said axle to turn said platen, a separately revoluble portion on said platen axle, devices coöperating with said platen to cause work-sheets passed

- 5 around the platen to be fed together when the swing frame is in its normal position, and devices coöperating with said separately revoluble portion adapted to independently drive certain of said work-sheets relatively 10 to the others when the swing frame is swung.

16. In a typewriting machine, the combination with a traveling carriage and a platen therein, of a swing frame, an axle

- 15 for said platen journaled in said frame, a separately revoluble portion on said platen axle, devices coöperating with said platen to cause work-sheets passed around the platen to be fed together when the swing frame is 20 in its normal position, normally ineffective feed rolls adapted to hold certain of said work-sheets against said portion, driving mechanism for said portion operated by the swinging of the swing frame, and means for 25 first making said feed rolls effective and then revolving said portion by the swinging of the swing frame.

17. In a typewriting machine, in combination, a revoluble platen, a platen-axle, 30 separately-revoluble sections mounted at the ends of said platen, and constituting extensions thereof, a platen-lifting frame in which said axle is mounted, feed-rolls with which the platen coöperates when in depressed position, auxiliary feed-rolls to co-operate with said sections, carried on said lifting frame, said auxiliary feed-rolls being normally spaced from said sections, means to cause said auxiliary rolls to engage said sections before the platen is lifted, and means effective at the end of the movement of the lifting frame to actuate said sections, and concomitantly increase the pressure of said auxiliary rolls thereon.

- 45 18. In a typewriting machine, in combination, a revoluble platen, separately-revoluble extensions of said platen to receive the margins of a record-sheet extending beyond the ends of said platen, feed-rolls to 50 coöperate with said platen, to feed work-sheets, including said record-sheet, auxiliary feed-rolls to coöperate with said extensions, means for separating said platen and the feed-rolls associated therewith, latching 55 means to prevent actuation of said separating means, means whereby release of said latching means will cause said auxiliary rolls to be pressed against said extensions, and means effective at the end of the separating 60 action to effect an increased pressure of said auxiliary rolls on said extensions,

and concomitantly to actuate said extensions to advance the record-sheet with reference to the rest of the work-sheets.

19. In a typewriting machine, in combination, a revoluble platen, independently revoluble members, forming extensions of said platen, feed-rolls to coöperate with said platen, a lifting frame in which said platen is mounted for movement away from said feed-rolls to release the work, auxiliary rolls to coöperate with said members, mounted on said lifting frame, a ratchet-wheel connected with each of said members, a pawl to coöperate with each of said ratchets, a carrier 70 for each of said pawls, a stop to limit the return movement of said pawl-carrier, and means, including a spring, connecting each of said pawl-carriers with the corresponding auxiliary roll, whereby said auxiliary roll 75 will be urged toward the adjacent revoluble member, and the pawl-carrier toward the stop, actuation of said pawl-carrier tending to increase the pressure of said auxiliary rolls on said members.

20. In a typewriting machine, in combination, a platen, a frame in which said platen is revolvably mounted, independently-revoluble sections, coaxial with said platen, and constituting extensions thereof, means 90 for actuating said sections, including a ratchet-wheel connected with each of said sections, a pawl to coöperate with each of said ratchet-wheels, and a carrier for each of said pawls mounted to swing about the axis 95 of said platen, an auxiliary feed-roll to co-operate with each of said sections, a stop to limit the return movement of each of said pawl-carriers, and means, including a spring for urging each of said auxiliary feed-rolls 100 toward the adjacent section, and the corresponding pawl-carrier against its stop.

21. In a typewriting machine, in combination, a revoluble platen, independently-revoluble members coaxial therewith, and forming extensions thereof, feed-rolls to co-operate with said platen, auxiliary feed-rolls to coöperate with said members, means for normally maintaining said platen and the corresponding feed-rolls in coöoperative relation, means whereby said platen and the corresponding feed-rolls may be separated, means normally maintaining said auxiliary feed-rolls spaced from said members, and means whereby said auxiliary feed-rolls 110 will be rendered effective by actuation of said separating means.
